UNITED STATES PATENT OFFICE

DENNIS P. BROPHY, OF NOKOMIS, ILLINOIS.

MAIL-BAG.

SPECIFICATION forming part of Letters Patent No. 331,472, dated December 1, 1885.

Application filed May 18, 1885. Serial No. 165,937. (No model.)

To all whom it may concern:

Be it known that I, DENNIS P. BROPHY, of Nokomis, Montgomery county, Illinois, have invented a new and useful Improvement in 5 Mail-Bags, of which the following is a full, clear, and exact description.

The object of my invention is to provide a new and improved mail-bag provided at the mouth with spring-straps, which keep the 10 mouth of the bag open when the flap is raised and closed when the flap is lowered.

The invention consists in the combination, with a mail-bag having a flap, of spring-straps secured on the flap and on the bag at the 15 mouth, and of a lock-plate and lock-casing secured on the flap and mouth part of the bag, respectively.

The invention also consists in parts and details and combinations of the same, as will 20 be fully set forth hereinafter.

Reference is to be had to the accompanying drawings, forming part of this specification, in which similar letters of reference indicate corresponding parts in both figures.

25 Figure 1 is a front view of my improved mail-bag, the flap being raised. Fig. 2 is a sectional plan view of the same on the line *x x*, Fig. 1.

The mail pouch or bag A is provided with 30 the flap B for covering the mouth, and on the inside of the said flap two spring-metal straps, C, are secured, which extend from a lock-plate, K, on the flap to the ends of the flap, where they are secured to metal end pieces, D, secured on the inner surface of the flap and having their lower ends hinged on heads or buttons E, which are swiveled on metal clips H, secured on the bag or pouch at the ends of 35 the mouth. Spring-metal straps F have their outer ends secured to the clips H and extended to a lock-casing, J, on the front of the bag at the middle of the mouth-edge, the straps being held by clips or other devices on the bag. The lock-plate K is provided with a 40 rib, L, which fits in a groove, M, in the casing J, and is there held by suitable locking devices

of any well-known construction in the casing J.

The spring-straps C and F have their outer ends bent in such a manner that when the bag 50 is open the outer ends of the bag are inclined toward each other and hold the bag open, and when the flap is swung down the straps C rest on the straps F and hold the flap in place.

By swinging the flap B down on the front 55 of the bag the rib L is brought into the groove M in the casing J and automatically locked, the spring-straps C F having the requisite sliding action to permit of such swinging action of the flaps.

Having thus described my invention, I claim as new and desire to secure by Letters Patent—

1. The combination, with a mail-bag having a flap adapted to close over the mouth, of 60 spring-straps secured on the flap and on the bag at the mouth, substantially as herein shown and described.

2. The combination, with a mail-bag having a flap at the mouth, of springs secured to the flap and to the bag at the mouth, and a lock-plate and casing secured on the flap and bag, 65 substantially as herein shown and described.

3. The combination, with a mail-bag having the flap B at the mouth, of the lock-plate K on the flap, the spring-straps C, secured on 75 the flap, the end pieces, D, secured on the ends of the flap and hinged on buttons E, the clips H on the bag, in which clips the buttons E are swiveled, the spring-straps F on the bag, and the lock-casing J on the bag, substantially as herein shown and described.

4. The combination, with a mail-bag having a flap, of end pieces on the ends of the flap, clips on the sides of the bag at the mouth, and of buttons swiveled on the clips, in which buttons the end pieces on the flap are pivoted, 80 substantially as herein shown and described.

DENNIS P. BROPHY.
